Primary Examiner — Vy N Koenig(74) *Attorney, Agent, or Firm* — Innovation Capital Law Group, LLP; Vic Lin(57) **CLAIM**

The ornamental design for a compact disc cover, as shown and described.

DESCRIPTION

FIG. 1 is a front perspective view of a compact disc cover showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right elevation view thereof;

FIG. 7 is a left elevation view thereof; and,

FIG. 8 is an exploded perspective view thereof.

The broken lines in the figures are for the purpose of illustrating portions of the compact disc cover that form no part of the claimed design.
